UNITED STATES PATENT OFFICE.

CHARLES B. MOORE, OF EVANSTON, ILLINOIS, ASSIGNOR, BY MESNE ASSIGNMENTS,
TO AMERICAN ARCH COMPANY, OF NEW YORK, N. Y., A CORPORATION OF DELA-
WARE.

LOCOMOTIVE-BOILER FURNACE.

1,138,038.

Specification of Letters Patent.

Patented May 4, 1915.

Application filed December 18, 1911. Serial No. 666,341.

To all whom it may concern:

Be it known that I, CHARLES B. MOORE, a citizen of the United States, resident of Evanston, in the county of Cook and State 5 of Illinois, have invented certain new and useful Improvements in Locomotive-Boiler Furnaces, of which the following is a specification.

My invention relates to locomotive boiler 10 furnaces and has particular reference to refractory baffles, walls or so-called arches for locomotive fireboxes.

It is well known that it enhances the efficiency of locomotive boilers to equip their 15 fireboxes with so-called water-circulating tubes. These tubes usually extend from the lower portion of the flue sheet rearwardly and upwardly to the upper portion of the rear sheet of the firebox. Some locomotives 20 are so designed that it is possible to equip them with only two of these tubes, on account of the shallowness of the throat sheet due to the nearness of the lower row of flues to the grate. In such instances the circulating 25 tubes are usually arranged one at either side of the firebox, and the special object of my invention is to provide a refractory arch particularly adapted for installation and use in such fireboxes.

30 A further object of my invention is to provide an arch of light construction adapted to fulfil the above conditions, and one which will not only retard or check the flow of gases from the grate to the flues, but will also break up and intermingle the various strata and layers of gases and deflect and direct them on many intersecting lines through the firebox, to the end that substantially perfect combustion may be established 35 and maintained in the firebox, and also that the combustible gases and fuel particles may be completely oxidized before they escape, through the flues.

40 A still further object is to provide an arch having the above characteristics which shall be built of a minimum number of brick forms or patterns, arranged to be supported upon the two tubes without the necessity of providing supporting lugs upon the side sheets, and parts of which may be removed 45 for repairs without disturbing the balance of the arch.

50 My invention consists in the several novel constructions and the combinations and relations of parts hereinafter set forth and de-

scribed and particularly pointed out in the appended claims; and will be readily understood upon reference to the accompanying drawings in which I have illustrated a structure which, in a preferred form, embodies 60 the several features of my invention.

In these drawings, which form a part of this specification; Figure 1 is a plan sectional view of a locomotive firebox provided with an arch constructed in accordance with my invention and taken on the line 1—1 of Fig. 2; Fig. 2 is a vertical central longitudinal section of the firebox and arch on the line 2—2 of Fig. 1; Fig. 3 is a vertical transverse sectional view on the line 3—3 of Fig. 2; Fig. 4 is a detail transverse sectional view of the arch on the line 4—4 of Fig. 1; Fig. 5 is a section similar to Fig. 4 taken on the line 5—5 of Fig. 1; and Fig. 6 is a longitudinal detail sectional view of the arch on the line 6—6 of Fig. 1.

My invention may be embodied in arches of varying details of construction and location in the firebox. I have, however, confined the illustrations of the invention to a 80 so-called refractory front arch which extends from side sheet to side sheet of the firebox, and which practically abuts the flue sheet, but I desire that it shall be understood that my invention is not confined or 85 limited to this specific structure and location of arch.

A locomotive firebox, as shown in the drawings, is made up of a flue sheet 2, the side sheets 3, 3, the crown sheet 4 and the 90 rear sheet 5. The firebox is equipped with a grate 6 at its lower end. The rear sheet contains the flue door or opening 7. The flues 8 lead forward from the flue sheet.

9, 9 are suitably positioned longitudinal, 95 arch supporting or circulating tubes, the same being inclined rearwardly and upwardly from the flue sheet. As usual they extend from the lower part of the flue sheet to the upper part of the rear sheet 5 and 100 serve to increase the circulation of water between the front and rear water legs of the boiler. These tubes are quite widely separated on account of the nearness of the lower flues to the grate, and my novel construction 105 of arch is particularly adapted for bridging, covering or arching the space between these widely separated tubes with a refractory body which depends upon the tubes for its support.

The office of a so-called front arch is to prevent the direct flow of gases and combustible particles from the grate to the flues and to force them toward the rear end and 5 side sheets of the firebox and thus cause the combustion to take place, throughout the length of the firebox, the object being to insure uniform distribution of heat over substantially the whole interior of the firebox 10 and especially along the whole length of the crown sheet. Such an arch or baffle, which is composed of comparatively light or thin members, quickly attains the maximum heat of the firebox, when the boiler is 15 being put into commission, and as quickly loses its heat when the fire is drawn. Both of these features are valuable in that the steaming qualities of the boiler are increased and when the fire is drawn there is not a 20 great mass of highly heated firebrick to continue the production of steam when it is not required. Further, the thin walls, projections or ribs on the arch quickly attain incandescence and thereby aid the ignition 25 of the gases and fuel particles and enhance the production of perfect combustion.

I build my arches of a number of refractory parts or sections so disposed or arranged as to present a large superficial area 30 or ignition surface, and also to enhance the retarding and admixing effects of the arch upon the gases of combustion.

In carrying out my invention I employ a considerable number of independent refractory bricks generally of several different shapes and assemble them in a way to secure the advantages above enumerated and others hereinafter mentioned.

A special feature of my invention resides 40 in a refractory arch which occupies an inclined position in the firebox, and is made up of two particular kinds of bricks, the one kind being supporting bricks or spans that are supported by the arch tubes 9 and which 45 are separated by considerable spaces, and the other kind being thin cover or panel bricks that rest on the supporting bricks and substantially and practically close the spaces between them. I usually make the supporting 50 bricks deeper or thicker than the panel bricks and it will be readily seen that this construction provides cavities or gas mixing pockets upon the under surface of the arch irrespective of the shape of the individual 55 bricks themselves and I add to the effectiveness of the arch by inclining parts of the arch at different angles transversely of the firebox thereby providing surfaces which tend to deflect the currents of the gas at 60 various angles both transversely and longitudinally through the firebox. I make the supporting bricks, members or spans of sufficient strength to support their own weight and the weight of the superposed cover 65 bricks. The sizes of the spans or support-

ing bricks and the disposition thereof in the firebox are determined by the position of and the distance between their points of support in the firebox, *i. e.*, the spacing of the tubes 9 and the distances between the 70 sides of the box and the adjacent tubes. In all cases, the several supporting and cover bricks, as herein shown, should be small enough to be handled easily, and without difficulty pass through the furnace door. 75 As the cover or panel bricks have no weight to support, and are subjected to little if any strain, they may be both thin and light. A desirable quality of arches of this character is that they shall wear out evenly and, as 80 the supporting bricks necessarily bear the brunt of the scouring action of the cinders and fuel particles, the cover bricks being somewhat protected from this effect, the cover bricks may be made considerably lighter than the supporting bricks and yet be as long-lived. Being made up of small units or individual pieces, my arch can be built with a minimum expenditure of time and labor, and being made up of individually supported sections, the whole of the arch need not be taken down to effect repairs on any one portion of the firebox.

Another advantage inherent in this form of arch results from the overlapped joints 95 between the supporting and panel bricks. These joints are to a great extent protected from the fusing action of the slag formed in the firebox and the arch does not become a rigid mass, but is what might be termed 100 "flexible" in that it can accommodate itself to slight changes in form, shape and dimension of the firebox without being broken up or disintegrated.

In the form of my invention, as illustrated in the drawings, the arch consists of two spans or rows of supporting bricks *a*, separated longitudinally in the firebox and held in proper relative position by means of a row of cover or panel bricks *b*. In this particular arch the tubes 9 are substantially midway between the center of the firebox and the respective sheet 3 and each of the spans or rows of supporting bricks comprises a center section and two end sections. The center section is composed of two of the supporting bricks *a* the combined length of which is greater than the distance between the tubes. These bricks form a self-supporting arch or span resting upon and extending between the tubes. These center span bricks abut midway between tubes and are preferably provided on their abutting ends with interlocking complementary tongues *a'* and grooves *a''* to prevent relative vertical movement of these abutting ends. The end sections of said span each consists of one of the span bricks *a* which is supported by a tube and is longer than the space between the tube and the side sheet, and consequently 110 115 120 125 130 135 140

occupies an upwardly inclined position leaning against or wedgingly abutting the respective side sheet. The two spans or rows of span bricks are separated by a considerable distance and the space between them is closed by the cover bricks b . In order to keep the back or the top of the arch smooth, I let these cover bricks into the upper edges of the supporting bricks forming the bricks a with gains or with sunken shoulders for this purpose. These cover bricks are preferably transversely shorter than the supporting bricks and I usually form them so that two cover bricks rest upon and fill the space between two adjacent or oppositely arranged supporting bricks. This construction lends itself readily to the building of arches of varying lengths as it is only necessary to make the cover bricks longer or shorter, thus spacing the rows of supporting bricks closer or farther apart, and thereby producing an arch of the desired length. The cover bricks being comparatively narrow and thin, they can be of considerable length and yet be easily handled and readily passed through the fire door. The cover bricks being positioned, as described, with their ends abutting the tops of the supporting bricks, they retain the spans in spaced relation and the overlapping joint formed between the cover bricks and supporting bricks, in a practical sense, protects the abutting surfaces from the cementing action of the slag. For the purpose of more securely retaining the span bricks in position, the cover bricks are extended downwardly between the side faces of the supporting bricks and abut therewith. Each of the panel bricks is provided with a comparatively deep cavity or pocket b' extending nearly the whole length and width thereof, and forming comparatively narrow marginal edges or ribs b'' on its under surface. This construction serves two important functions, that of lightening the cover bricks without materially reducing their strength and that of breaking up the top of the comparatively large cavity between the supporting bricks and producing a plurality of gas-mixing pockets and deflecting surfaces and cavities of smaller area. The row of cover bricks is coextensive with the supporting bricks and the outer members thereof preferably abut the side sheets of the firebox similar to the abutment therewith of the supporting bricks a .

The span bricks are provided with large tapered projections a^3 extending from one transverse edge. These projections serve to space the first row of supporting bricks in position from the flue sheet and those on the upper end of the arch form a serrated or notched edge thereon which serves to break up and intermingle the currents of gases passing over or around this edge. The open-

ings or spaces formed between the lower row of bricks and the flue sheet serve to permit the discharge of cinders and ash from the upper surface of the arch to the fuel bed. The supporting bricks are provided on their under surfaces with large cavities a^4 of substantially the same outline as the brick itself and providing the under surfaces with comparatively narrow or thin marginal edges or ribs a^5 . These cavities and marginal ribs enhance the desirable qualities and functions of the arch in that they assist in the deflection of the gas currents and the ignition of the fuel.

One of the advantageous results accruing from this construction of arch is that the combustion space below the arch is considerably enlarged over what it would be were the boiler equipped with a flat arch, and the upwardly inclined side portions of the arch expose a larger portion of the side sheets to the high temperature of the combustion part of the firebox. Also the upwardly inclined side portions of the arch make it possible to eliminate supporting lugs or attachments to the side sheet and the side members may be readily removed for the purpose of repairing the side sheets or stay-bolts without disturbing the center portion of the arch. And again, the center portion of the arch may be removed when it is desired to work upon or repair the flue sheet without disturbing the side portions of the arch. The increased depth of the combustion part of the firebox, due to this gabled construction of arch, is a particularly valuable feature in a firebox of this kind because of the fact that deep fires are often carried and cheap help and unskilled firemen are often necessarily employed, and if the arch approaches too close to the grate the combustion space is liable to be clogged or choked adjacent to the flue sheet.

Although I have herein shown supporting members or spans of the kind adapted to the peculiar arrangement of arch tubes disclosed, and the supporting members provided with the tapered projections, it is obvious that my invention permits of other arrangements of such tubes, and that the shapes and relations of the span bricks and cover bricks may be considerably modified without departing from the spirit of my invention; therefore I do not confine the invention to the specific structure herein shown and described.

Having thus described my invention, I claim as new and desire to secure by Letters Patent:

1. A locomotive boiler firebox having two inclined arch tubes therein, in combination with a refractory arch resting upon and supported by said tubes and comprising two rows of supporting bricks spaced apart and a row of cover bricks arranged therebe-

- tween, each of said rows of supporting bricks comprising a pair of bricks resting upon the tubes and holding each other in position, and two similar end bricks resting upon the tubes and wedgingly engaging the side sheets, the under surface of said bricks being provided with large gas-mixing cavities of irregular contour, and their outer edges being provided with large tapered projections, said cover bricks resting upon, extending between and spacing said supporting bricks apart and substantially filling the opening between said rows of supporting bricks from side to side of the firebox.
2. A locomotive firebox equipped with two inclined arch tubes, in combination with a refractory arch of gabled form, comprising a center section and two side sections, said center section consisting of two parts supported by said tubes and leaning against and relatively held in position by each other and forming a central longitudinally disposed gable, each of the side sections resting on a tube and abutting the adjacent side sheet and forming a partial gable at each side of the firebox, and each said section having a relatively large tapered projection on each of its ends.
3. A locomotive firebox having two arch tubes therein, in combination with a plurality of arch spans supported by said tubes and spaced apart, each said span comprising a center section and two outer or end sections, the center section composed of two bricks resting upon and arched between said tubes, and each of the outer sections comprising a single brick supported by a tube and inclined upwardly and outwardly against the respective side sheet, each of said span bricks being provided with a single large tapered projection on its outer edge, and panel bricks extending between said spans spacing them apart, closing the spaces between respective spans and therewith completing an arch.
4. A locomotive firebox having two arch tubes, in combination with a plurality of arch spans supported by said tubes and spaced apart at different heights, said spans each comprising a center section and two outer or end sections, the center section composed of two bricks abutting at their inner ends and resting upon and arched between
- said tubes, and each of the outer sections composed of a single brick supported by a tube and inclined upwardly and outwardly against the adjacent side sheet, the lower span bricks having large tapered projections for contact with the flue sheet, and the upper span bricks each having a similar large tapered projection on its upper edge and panel or cover bricks extending between said spans spacing them apart and closing the spaces between respective spans.
5. A locomotive boiler firebox having a pair of inclined circulating tubes therein, in combination with a refractory body resting upon and supported by said tubes extending from side sheet to side sheet and resting against the flue sheet, said body comprising a plurality of transverse rows of supporting and cover bricks, each row of supporting bricks composed of a center span made up of two bricks supported on respective tubes and leaning against and interlocked with each other, and end spans each including a single brick resting upon a tube and leaning against the adjacent side sheet, the inner edge of the arch having a number of relatively large tapered projections arranged between the arch supports and adapted to contact with the flue sheet and hold the main part of the arch spaced therefrom, and said cover bricks arranged between said spans retaining said spans in spaced relation and closing the openings between them.
6. A locomotive boiler firebox, its side sheets and longitudinal inclined arch tubes, in combination with a plurality of longitudinal rows of refractory bricks, the outer rows being arranged between and supported by respective side sheets and tubes and the intermediate rows being supported by said tubes, and the upper rear end brick of each said longitudinal row having an upwardly and rearwardly extending projection, and its underside containing a gas-mixing pocket of irregular contour.

In testimony whereof, I have hereunto set my hand, this 5th day of December, 1911, 100 in the presence of two subscribing witnesses.

CHARLES B. MOORE.
